(57) **CLAIM**

The ornamental design for a pressurized air delivery console, as shown and described.

DESCRIPTION

FIG. 1 is a front perspective view of a pressurized air delivery console according to a first embodiment showing our new ornamental design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is another perspective view thereof;

FIG. 9 is a front perspective view of a pressurized air delivery console according to a second embodiment showing our new ornamental design;

FIG. 10 is a front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is another perspective view thereof.

The broken lines represent environmental structure or unclaimed portions of the pressurized air delivery console and do not form a portion of the claimed design.

The use of both stippling and line-shading in FIGS. 1-8 indicates different materials or tones.
